UNITED STATES PATENT OFFICE.

GEORGE DEMACAKOS, OF CHICAGO, ILLINOIS.

COMBINATION COAT AND VEST.

No. 866,342.

Specification of Letters Patent.

Patented Sept. 17, 1907.

Application filed July 31, 1907. Serial No. 386,440.

To all whom it may concern:

Be it known that I, GEORGE DEMACAKOS, a citizen of the United States, residing at Chicago, in the county of Cook and State of Illinois, have invented new and 5 useful Improvements in Combination Coats and Vests, of which the following is a specification.

My invention pertains to garments; and it consists in the peculiar and advantageous coöperating coat and vest, hereinafter described and claimed, embodying 10 such construction that they may be expeditiously and easily adjusted so as to be worn to advantage in either warm weather or cold weather.

In the drawings accompanying and forming part of this specification: Figure 1 is a view showing the coat 15 and vest of my invention and also showing the front portions of the vest as inclosed and hidden from view in the front portions of the coat; the vest being illustrated with its back removed. Fig. 2 is a view similar to Fig. 1 but showing the front portions of the vest as 20 removed from the front and side portions of the coat. Fig. 3 is an enlarged detail vertical section illustrative of the manner in which the front and side portions of the vest are detachably secured in the front and side 25 portions of the coat. Fig. 4 is a side elevation illustrating one front and side portion of the coat and the corresponding vest portion arranged in and hidden by the coat portion. Fig. 5 is a front view of the vest with the detachable back in its proper position for use. Fig. 6 is a rear view of the vest with the detachable back 30 removed.

Similar letters designate corresponding parts in all of the views of the drawings, referring to which:

A is the coat of my improvements. In general the said coat is of the ordinary well known construction, 35 but it is peculiar in that it is provided at the inner sides of its side and front portions *a* with receptacles *b* designed to contain and hide the side and front portions of the vest after the manner shown by dotted lines in Figs. 1 and 4. The mouths of the said receptacles *b* 40 extend from about the middles of the arm pits *c* of the coat portions *a* to a point *d* adjacent to the lower ends of said portions *a*; and in the preferred embodiment of my invention the said receptacles are formed by pieces of lining *e* which are stitched, as indicated by *f*, along 45 their edges to the inner sides of the portions *a* except between the mentioned points *c* and *d*. Thus it will be apparent that the receptacles *e* are provided, with mouths extending from the points *c* to the points *d*, while the inner sides of the portions *a* present the appearance 50 of neatly lined coat portions. At their inner sides and at points adjacent to the mouths of the receptacles *b*, the pieces of lining *e* are provided with fastener members *g* designed to coöperate with complementary fastener members on the vest portions in 55 detachably securing the latter in the receptacles *b*.

B is the vest of my improvements. This vest is made up of side and front portions *h*, a yoke *i* connecting in a permanent manner the upper ends of said portions *h*, back straps *j* connected to the portions *h* and designed to be detachably connected together through the 60 medium of a buckle *k* or other suitable means, and a removable back *l*; the latter being designed for use only when the weather is cold and it is desirable to provide an extra thickness of cloth at the back of the person wearing my novel coat and vest. The yoke *i* 65 of the vest is provided at its forward side with a button-hole *m* for the engagement of a button *n* at the back of the upper portion of the back *l*; and it is also provided at points adjacent to the portions *h* and on its forward side with fastener members *p* designed to coöperate 70 with fastener members *r* on the back *l* in detachably connecting the back *l* to the yoke *i*. At opposite sides of its lower portion the removable back *l* is provided with straps *s*, one of which is provided with a buckle *t*, whereby the straps may be fastened together in front 75 of the stomach of the wearer with a view of holding the back *l* close against the back of the wearer.

By virtue of the construction described it will be apparent that when the weather is warm and it is desirable to have the garment as a whole thin and cool 80 at the back, the back *l* may be detached from the yoke *i* and entirely removed from the garment; and it will also be appreciated that when the weather conditions are such that an additional thickness of cloth is desirable at the back of the wearer, the back *l* may be ex- 85 peditiously and easily attached to the yoke *i*, and the straps *s* may be as readily fastened about the body of the wearer to retain the lower portion of the back *l* snug against the wearer.

When the back *l* is removed from the remainder of 90 the vest, the vest may be worn in the usual way, as shown in Fig. 2, or else the side and front portions *h* of the vest may be positioned in the receptacles *b* of the coat portions *a* and entirely hidden by the inner walls *e* of said receptacles, after the manner illustrated in 95 Figs. 1 and 4. When the vest portions *h* are placed in the receptacles *b* as stated, the fastener members *g* of the pieces of lining *e* are engaged with the fastener members *u* on the inner sides of the vest portions *h*. Because of this latter provision it will be readily observed that the vest portions *h* are held in a neat and smooth manner in the receptacles *b*, with the result that the coat presents the same finished appearance as a neatly lined coat of ordinary construction worn without a vest. It will also be gathered that because of the 100 vest having but the yoke *i* and the straps *j* at the back, it adds but little to the weight of the combined garment and does not render the coat any warmer at the back than an ordinary coat worn without a vest.

When the combined garment is in use and it is de- 110

sired for any reason to display the vest, the vest portions *h* are detached from the linings *e* and removed from the receptacles *b*, and positioned and fastened in front of the body in the ordinary manner, when, as 5 will be readily apparent and as shown in Fig. 2, the combined garment will present the same finished appearance as a neatly fitting coat and vest of the ordinary construction. Then if the weather conditions are such that it is desirable to use the back *l*, the said back may 10 be attached to the yoke *i*, and its straps *s* may be passed between the vest portions *h* and the body of the wearer, and may be fastened through the buckle *t* in front of the body of the wearer but under the side and front portions *h* which will entirely hide them from view. 15 In virtue of the construction described, it will be observed that the vest of my improvements, with the exception of the back *l* is carried by the coat and in a neatly arranged manner when the vest is not in use; and it will also be noted that the back *l* of the vest is 20 susceptible of being compactly folded and carried in one of the pockets of the coat.

In addition to the practical advantages herein ascribed to my improvements, it will be noted that the said improvements are no more expensive than an 25 ordinary coat and vest of corresponding quality, and that the said improvements are quite as durable as an ordinary coat and vest.

The construction herein shown and described constitutes the best embodiment of my invention of which 30 I am cognizant but it is obvious that in practice such changes or modifications may be made as fairly fall within the scope of my invention as defined in the claims appended.

Having described my invention, what I claim and desire to secure by Letters-Patent, is:

1. A vest comprising side and front portions having fastener members on their inner sides, a yoke permanently connecting the upper ends of said side and front portions and provided at its forward side with fastener members, back straps connected to the lower ends of the side and front portions and equipped to be adjustably connected together, and a detachable back having fastener members adjacent to its upper end for coöperating with the fastener members of the yoke and also having straps on its lower portion provided with means whereby they may be adjustably connected in front of the body, in combination with a coat having side and front portions and also having receptacles at the inner sides of said side and front portions; the said receptacles being formed by linings which are stitched to side and front portions except between points at the rear edges of the lining, and the said linings being provided on their inner sides with fastener members arranged to coöperate with the complementary members of the vest portions. 45

2. A vest for the purpose described made up of side and front portions, a yoke extending between and permanently connecting the upper ends of said side and front portions and provided at its forward side with fastener members, back straps connected to the lower ends of the side and front portions and equipped to be adjustably connected together, and a detachable back having fastening members adjacent to its upper end for coöperating with the fastener members of the yoke and also having straps on its lower portion provided with means whereby they may be adjustably connected in front of the body. 60

In testimony whereof I have hereunto set my hand in presence of two subscribing witnesses.

GEORGE DEMACAKOS.
